UNITED STATES PATENT OFFICE.

WILLIAM LUDLUM, OF MOUNT VERNON, NEW YORK.

DESIGN FOR A WATCH-CHARM.

Specification forming part of Design No. **11,357**, dated August 19, 1879; application filed July 8, 1879.
[Term of patent 3½ years.]

To all whom it may concern:

Be it known that I, WILLIAM LUDLUM, of Mount Vernon, in the county of Westchester and State of New York, have invented a new Design for Watch-Charms, of which the following is a specification.

This is especially intended to be applied to the telescopic cases of such instruments as pencils, watch-keys, and tooth-picks, which are known in the jewelry trade as "watch-charms," and are used or worn as pendants from watch-chains.

The accompanying drawing represents a side elevation of a watch-charm of my design.

The charm is composed of a round body or shaft, A, here represented as slightly tapering or conical in form, a molded terminal, B, at its lower end, and a molded terminal or head, C, at its opposite end.

As here represented, the moldings at the lower end consist of a fillet, a, of much larger diameter than the body or shaft A, and connected therewith by an ogee molding, b. A rounded projection, c, extends below the fillet a.

The terminal or head C, as here represented, consists of two beads, d, joined to the body or shaft A by a molding, e, here shown as a cyma recta.

At the top of the charm I have represented a knob, f, through which passes a ring, g, which may serve to suspend the charm, and also posts h, shown as two in number.

What I claim as my invention, and desire to secure by Letters Patent, is—

1. The design for a watch-charm of the configuration described, consisting, essentially, of the round body or shaft A, molded terminal B, molded terminal or head C, and posts h, substantially as shown in the accompanying illustration.

2. The design for a watch-charm of the configuration described, consisting of the tapering or conical body or shaft A, molded terminal B, molded terminal or head C, and posts h, substantially as shown and described.

3. The design for a watch-charm of the configuration described, consisting of the tapering or conical body or shaft A, molded terminal B, molded terminal or head C, posts h, knob f, and ring g, substantially as shown and described.

WM. LUDLUM.
